PILE SHIELD

John Upton, Wayland, Mass., assignor, by direct and mesne assignments, to Anderson Products, Inc., Cambridge, Mass., a corporation of Massachusetts

Application August 6, 1937, Serial No. 157,709

16 Claims. (Cl. 61—54)

This invention pertains to a means and method of protecting wooden piles such as are used in various forms of marine construction work.

The wooden piles that are in general use in 5 harbors, both in this country and abroad, are subject to severe damage by certain marine amphipod Crustacea, particularly the teredo navalis, Limnoria and Chelura. These forms of marine life are found in large numbers in practically all 10 harbors in the tropic and temperate zones.

Many ways have been tried to eliminate the 15 destructive results occasioned by these animals. The piles have been treated by creosoting before being placed in the water. This has proved of material assistance, as the worms do not find 20 such conditions favorable. However, the great mass of the piles now in use in harbors are untreated and are being rapidly eaten away. The problem, therefore, that confronts those in charge 25 of maintaining marine structures, such as docks, wharves, piers, and the like, is how to prevent or arrest further destruction of the piling.

The prior art shows that many means in the 30 form of shields placed about the piles in one form or another have been attempted. The problem is one of long standing and involves structures of large cost and hence it is significant that up to the present time no satisfactory shield to prevent this damage has been devised.

Of those that have been used there is no record 35 that they have accomplished the result intended and it is common knowledge among authorities on this subject that there is no means available on the market today which can satisfactorily cure this condition.

It is well known that when a pile is surrounded 40 by sand or other divided inert material which will pack closely about a pile, circulation of water thereabout is checked and destructive animal life present in the pile is promptly eliminated, as the animals die upon the exclusion of oxygen which would normally be brought to them by water circulating about the pile. Thus, we find 45 that the portion of a pile which is embedded in the bottom is not attacked and likewise, if that portion of a pile extending from the bottom to the high water mark is surrounded by a column of sand which may be retained in position by a tubular member, the latter portion will also be 50 preserved from attack by these marine worms, or, if the worms have been present in the pile they will die shortly after the application of the column of sand or similar material.

This feature has long been known and many 55 attempts have been made to provide a tubular

shield about the pile extending from the bottom to above high water in which sand might be positioned. The theory is simple. The difficulty has resided in making a shield from which the sand will not escape. On its face this should not seem difficult but the situation in practice is this. In 5 harbors the mudline, that is, the surface of the bottom, constantly shifts from one cause or another. As harbors are deepened, the mud about the pile tends to slide gradually downwardly toward the deeper portions of the harbor and in this way portions of the pile which had previously been embedded in the bottom will become uncovered. Thus, any shield, whether of metal or concrete, which is affixed to a pile so that it may 10 not move longitudinally becomes of little use when the mudline has dropped below the bottom of the shield for upon arrival of this condition the worms promptly find the unprotected wood and recommence their destructive efforts.

The descending mudline condition has also been appreciated in the prior art as there have been devised pile shields which merely rest on the bottom and as the bottom is washed away the shield descends therewith and theoretically the 15 shield continuously holds the sand or other material within the shield about the pile. However, in practice this type of shield has not functioned as might normally have been expected for the 20 fact that the bottom inevitably washes away at 25 some portion about the circumference of the shield sufficient to provide a small opening between the harbor bottom and the bottom of the shield and immediately, upon the development of 30 this situation, the sand contained within the 35 shield promptly flows downwardly and out through the opening. That this can happen so readily is because sand, in water, is very fluid. To overcome this difficulty the prior art shows 40 the introduction of bottom closure devices, usually 45 in the form of inwardly extending radial sections or gaskets which fit more or less closely about the pile and are relied on to retain the sand within the shield. These, however, likewise have not 50 proved successful in preventing the escape of sand once the harbor bottom has washed away below the bottom of the shield at some point. The reasons why this last mentioned type of 55 shield has not functioned are somewhat complex, and need not be described in detail. It is believed sufficient to say that they will not work and no device of the prior art will be found in practical use, although the demand for such a unit is wide spread.

The foregoing recital of the general state of the prior art is made in order that the nature of my improvement, why it works, and what it does, may be more clearly understood.

- 5 My invention comprises a shield which may readily be positioned around a pile and after being filled with sand or other suitable material will thereafter satisfactorily hold the sand with negligible leakage about the pile, regardless of
10 any shifting that may take place in the mudline of the bottom in which the pile is driven. My invention may be used in connection with new piles to prevent subsequent destruction by the aforementioned Crustacea or it may be applied
15 to a pile already attacked with a result that such animal life will be killed and destruction arrested.

Other objects of my invention will become apparent as the description proceeds with the aid of the accompanying drawings, in which:

- 20 Fig. 1 shows two piles partially destroyed, around one of which my pile shield has been applied but not filled with sand or other protective material;

25 Fig. 2 is a perspective view of one of the upper sections of my pile shield;

Fig. 3 is a section on the line 3—3 of Fig. 2 illustrating the internal spacers used to prevent the pile from touching the shield;

30 Fig. 4 is a sectional detail showing the means for maintaining the sections in telescoping relation;

Fig. 5 is a plan view of the bottom section of my unit prior to application on a pile, showing a preferred form of sand check;

35 Fig. 6 is a section on the line 6—6 of Fig. 5;

Fig. 7 is a sectional view showing the device shown in Fig. 5 as applied to a pile including a skirt member attached to the bottom of the shield;

40 Fig. 8 shows one-half of a skirt adapted to be attached to the bottom of a shield, having its lower edge at an angle to conform with the slope of the bottom;

Fig. 9 is a section on the line 9—9 of Fig. 5
45 showing spring means for exercising downward pressure on the sand checks;

Fig. 10 is a section on the line 10—10 of Fig. 5 showing the hinge mechanism;

Fig. 11 is a section on the line 11—11 of Fig. 5
50 showing the nature of the overlapping segmental sand checks;

Fig. 12 is a view similar to Fig. 5 showing the bottom section with a modified form of sand check positioned about a pile;

55 Fig. 12a is a sectional perspective of the form of sand check shown in Fig. 12;

Fig. 13 illustrates the condition that prevails when my unit is in position about a pile and filled with sand or similar material;

60 Fig. 14 illustrates the manner in which my unit settles about the pile as the bottom is washed away while at the same time preventing the escape of the material within the unit;

Fig. 15 is a view similar to Fig. 13 with the exception that the shield has a sloping bottom skirt adapted to conform to the slope of the bottom;

Fig. 16 is a view similar to Fig. 14 showing the
70 situation after the sloping bottom of Fig. 15 has been washed away;

Fig. 17 shows a further modification of the sand checks in which the segmental sections are integral with the side wall;

75 Fig. 18 is a section on the line 18—18 of Fig.

17, the dotted line illustrating the position the sand check assumes when in position about a pile;

Fig. 19 is an elevation partly in section showing a replacement unit adapted for easy insertion
5 in the uppermost undamaged original section;

Fig. 20 is a sectional view showing a modified form of hook and spacer used in supporting one section on another;

Fig. 21 is a vertical section on the line 21—21
10 of Fig. 20 showing the manner in which the spacers hold the shield away from the side of the pile.

Referring now to Fig. 1 it will be seen that the
15 pile 2 is surrounded by a tube or shell composed of a plurality of sections 4 and 6 and a bottom section 8. The upper sections 4 and 6 may be of any convenient length and number provided, however, that the upper end of the topmost section is above the range of attack of the worms.
20

The bottom section 8 is of special construction
25 differing from sections 4 and 6 and will be described hereinafter. The tubular sections 4 and 6 may be made in any convenient manner in either one or more pieces, provided they may be positioned readily about the pile.

Fig. 2 shows one suitable form of section I have employed. In this case the section is a continuous sheet of relatively thin metal having suitable resistance to corrosion from the water.
30 A plurality of lugs 19 and 12 are secured adjacent the long edges of the tube to cooperate with bolts 14 for securing the unit about the pile after it has been slipped thereover or thereabout. At the bottom of each section are a plurality of combination hooks and spacers 16 one of which is shown in detail in Fig. 4. These hooks are so arranged that the section above may be lowered telescopically within the section below so that the hook portions 18 extend outside of the lower section thus to support the upper section thereabove. The portion of member 16 within the section, as at 20, is utilized as a spacing member to prevent the pile from coming in contact with the shell or tube, should the former not be centered with respect thereto. The distance between spacers 20 is governed by the diameter of the pile with which the shell is used.

The lowest regular section of the tube, in this case section 6, rests on a special bottom section 50 which is shown in Figs. 5, 6 and 7. This bottom section 8 is, in my preferred form, made in two halves, 22 and 24, having flanges 26 and 28 adapted to be bolted together to form a tubular member. The tube so formed is of the proper 55 diameter to allow the section immediately above to be telescopically installed and positioned by means of hooks 18.

Intermediate of the ends of the bottom section 8 are a plurality of segmental sections which I have termed sand checks. In Fig. 5 I have shown six sand checks, 32, 34, 36, 38, 40 and 42, the edges of which overlap and of which every other one, as 32, 34 and 36, overlies adjacent segments 38, 40 and 42. Considering 65 sand check 36 illustrative of the overlying sand checks it will be seen that it is hinged at 43 to a supporting portion 44 which is secured to the wall of the bottom section. The hinge construction is shown in Fig. 10 while Fig. 9 illustrates a 70 coil spring 45 that I use to urge the sand checks downwardly. One end of the spring rests on the shield wall, the other on the overlying sand check. Movement, however, below the horizontal is prohibited by the flange 46 of the sand check 75.

which engages the bottom of the horizontal portion of support 44.

The underlying sand checks 38, 40 and 42, hinged to supports 44 at 43, have their radial edges bent downwardly as at 48, shown in Fig. 11. This is to prevent binding when the sand checks are swung upwardly in assuming their position about a pile.

It will be observed in Figs. 1, 6, 7, 13, 14, 15 and 16 that there is a substantial distance between the sand checks and the lower edge of the bottom section to which the sand checks are attached. That portion of the shell which extends below the sand checks and which I term a skirt may be either an integral part of the bottom section or it may consist partly of the bottom section and a supplementary skirt bolted thereto. A skirt of the latter type is shown at 50 in Figs. 1, 7 and 17 and at 52 in Figs. 8 and 19. The skirt that extends below my sand checks constitutes an important part of my invention as will be explained hereinafter.

Figs. 12 and 12a show a modified form of sand check. In this case the segmental sections while similar in form to those shown in Fig. 5 are not hinged to, but rather are integral with, the supports 44 that are secured to the semi-cylindrical sections 22 and 24. When sand checks of this type are positioned about a pile they bend upwardly along the lines 54. Since the metal of which these checks may be made is relatively thin gauge, it may be necessary to provide additional spring means of some sort to more firmly urge the segments against the pile that centering of the pile may be definitely accomplished. Such spring means is shown at 56 in the form of a coiled spring having one end resting against the wall of the tube and the other end pressing downwardly on the sand check. Fig. 12 is also illustrative of the situation that develops when one of the sand checks comes to rest on some projection 55 that may extend from the pile, as for example, a portion not eaten away by the worms or a stub of a branch not cut off closely when the tree was felled. When an underlying segment happens to come to rest against a projection as shown it will of necessity raise the adjacent overlying sections a slight amount so that there may be clearance between the sand checks and the pile.

This, of course, is an undesirable condition, but, by virtue of the operation of my skirt 50 extending below the sand checks, escape of sand is prevented.

Fig. 17 illustrates a still further modification of the manner of construction of the sand checks. In this case, segments 58 are integral with the side wall 22, bending upwardly as at 60 in Fig. 18 when applied about a pile. Additional spring means, such as shown in Fig. 12a, may be used to urge the segments against the pile with greater force, if necessary, to maintain the lower end of the shield centered with respect to the pile.

Having thus described the general construction of my unit I shall now explain the method of application and operation in the prevention of the escape of sand or other material therefrom.

The two halves of the bottom section 8, each of which already has the sand checks properly positioned and fastened therein, and an appropriate skirt extending therebelow, are secured about the pile. In order to determine the proper

type of skirt to be used in connection with the bottom section, consideration is given to the nature of the bottom in which the pile is embedded. If the bottom is substantially level, a skirt of uniform width with such as 50 shown in Figs. 1, 7 and 17 is secured to the lower edge of the bottom section to provide a length of not less than 8 inches, in the ordinary case, from the sand check to the bottom of the skirt. If, however, the diameter of the tube is increased for use with piles of larger diameter, the distance from the bottom of the sand check to the bottom of the skirt should be correspondingly increased and conversely, if smaller tubes are used, the skirt length may be reduced. The reason for this will presently appear. If, on the other hand, the bottom in which the pile is embedded is sloping, as shown for example in Figs. 15, 16 and 19, then a skirt in the form of a short cylinder cut diagonally on one end is attached to the bottom of the bottom section. Two sections, as 52 in Fig. 8, bolted together will form this type of skirt. The slope of the bottom edge of the skirt is selected to approximate the slope of the bottom in which the pile is embedded. In every case, however, the intention is that when the shield rests on the bottom it shall penetrate the bottom a substantially uniform distance about its entire circumference. Of course, however, the bottom skirt and the bottom section may be made integral as at 49 in Figs. 12a, 13, 14, 15 and 16, but I have found it more convenient to follow the aforementioned procedure.

After a skirt has been selected to match the slope of the harbor bottom, the bottom section with skirt attached is forced downwardly along the pile and the first main section 6 is positioned thereupon with its lower end inside of bottom section 8. The hooks 18 of course support section 6 in position. The shield thus far assembled is then forced downwardly further and another section, as for example 4, is positioned on top of the preceding section in the same manner. This procedure continues until the tube thus assembled strikes bottom and the upper end is above the portion attacked by the Crustacea. Usually by this time, the weight of the tube itself will cause the lower edge of the skirt to cut into the bottom a distance determined by the nature of the bottom material. Such a condition is shown in Fig. 1. If, by any chance, the pile about which the shield is positioned is crooked, the shield will be able to conform to the pile because the telescoping joints are not rigidly connected and the tube may bend at these overlapping areas. This is a point of considerable importance as the number of warped and distorted piles is larger than might be supposed.

With the shield in its final vertical position about the pile and with the lower end embedded a suitable distance in the bottom, I have provided means in the form of my sand checks for accurately centering the lower end of the shield with respect to the pile. This is accomplished by making the sand checks of suitable size with respect to the pile with which they are to be used. By proper design, the sand checks will be swung upwardly when the shield is in settled position through an angle of approximately 30 degrees to assume the position shown in Figs. 1, 7, 12, 13, 14, 15 and 16. This angle, of course will be varied more or less as the size of the pile varies but, however, that may be, the over-

lapping segments forming the sand checks provide an inverted bottom section fitting relatively closely about the pile and having such flexibility that the bottom section with the sand checks attached is free to slide still further downwardly along the pile as the bottom material may be washed away.

The sand checks when set at an angle in the neighborhood of 30 degrees and urged downwardly by springs 45 or 56 provide an efficient and positive means for maintaining the pile centered with respect to the bottom section 8. Any lateral force that might be exerted against the bottom of the pile in any direction by movement of the current or bottom or otherwise will be successfully resisted by the sand checks because of their angle of engagement with the pile.

At this point I think it proper to emphasize the importance of spacers 29, which are shown in Figs. 1, 2, 3 and 4. It will be observed that these spacers do not extend within the shell a sufficient distance to definitely center the pile with respect to the shell. They do, however, effectively prevent the pile from coming in contact with the wall of the tube at any point. This is very important because I have found that if the pile, due to a warped or crooked condition, should touch the wall at any point a void will invariably be formed immediately below the point of contact when the tube is subsequently filled with sand. The formation of such a void would permit the Crustacea to continue their destruction at this point and, furthermore, should the void by chance be adjacent a joint of the tube it is possible that Crustacea might work their way through the joint to renew the damage to the pile.

The inward extent and circumferential spacing of the spacers 29 is determined by the diameter 49 of the pile coupled with the extent the pile deviates from its normal vertical axis. If the pile happened to be very crooked it would be necessary to have the spacers 29 extend inwardly a greater distance in order to be sure that the pile could not touch the wall.

With the unit in position as in Fig. 1, and, of course, filled with water, sand or other relatively finely divided inert material is introduced in any convenient manner at the top of the tube and as the tube is gradually filled the water therein is displaced. The sand begins to pile up on the sand checks and as this proceeds the sand checks are urged downwardly to exert greater pressure at their ends against the pile, minimizing whatever clearance may have been present initially. At the same time the weight of the sand, as it collects on the bottom formed by the sand checks, is transferred to the bottom section 8 through the supports 44 attached thereto with a result that the bottom edge of the skirt is driven deeper and deeper into the mud. A condition of equilibrium is reached when either the bottom edge of the skirt has gone so deeply into the mud that the mud within the skirt has risen high enough to engage the underside of the sand checks or a sufficient amount of sand has filtered between the sand checks to fill the small remaining space between the top of the mud within the skirt and the bottom of the sand checks.

In either event, the bottom edge of the shield is well embedded in the mud and there is no possibility of the shield rising as it, through the sand checks, carries the heavy load of the column of sand which fills the shield. A similar situation is developed when the diagonally cut

skirt is used and in such case a condition of equilibrium is reached after the lower edge of the skirt has been driven a substantial distance into the mud by virtue of the weight of the sand carried by the shield.

Where the bottom is very soft the heavy load imposed by the sand on the shell will cause it to sink a considerable distance into the bottom so that the mud line in many instances may be well above the sand checks. This situation is illustrated in Fig. 7. In other cases where the bottom is of a firmer nature the shield will settle to a lesser depth so that the mud line may be at or slightly below the level of the sand checks as illustrated for example in Figs. 1, 13 and 15. Where the bottom is quite hard the depth to which the shield will sink in the bottom is still less but, in any event, it will always penetrate the bottom sufficiently to adequately seal the sand within the tube.

It should be pointed out, however, that when the tube is first positioned about the pile and prior to being filled with sand the weight of the tube itself is not sufficiently great to drive it into even a soft bottom more than the depth of the skirt that extends below the sand checks. This is essential in order that the bottom material between the shell and the pile shall not extend upwardly far enough to raise the sand checks away from their normal position against the pile. If this latter situation were permitted to develop the sand with which the tube is subsequently filled would be less securely contained within the tube and less of its weight would be transferred through the sand checks to the shield. If, upon inspection of the bottom, it was determined that the bottom was so soft that the shield under its own weight would settle a distance greater than the length of the normal skirt, then it is anticipated that a longer skirt would be used in such a situation.

The mechanism thus far described is obviously adequate to hold a column of sand about a pile, escape at the bottom being prevented by the depth of penetration of the lower end of the tube. However, it is necessary to make provision for the situation that develops when the mud line is lowered as the bottom is washed away. As has been pointed out before, the depth to which the shield sinks in the bottom is determined by the nature of the bottom. All bottom material is in a more or less fluid state and, of course, is thoroughly saturated with water. At the position of equilibrium, it is apparent that the bottom material under the shield stops further descent when the lateral support offered by the adjacent bottom material is equal to the outward force exerted by that portion of the bottom which is immediately below the shield. When the surface material is washed away as at 62 in Fig. 14 it is apparent that the lateral support accorded the bottom material located at 64 in Fig. 13 is largely eliminated with the result that the material 64 of Fig. 13 moves laterally to the position shown in Fig. 14. With this portion of the bottom displaced the loaded shield moves downwardly until a new position of equilibrium is reached as shown in Fig. 14. Naturally this gradual settling of the shield is a continuous process which takes place as rapidly as lateral support of bottom material 64 is removed to an extent sufficient to permit the supporting material to shift sidewise. The heavy load imposed on the shield through the sand checks is always adequate to keep the lower edge of the shield a sufficient dis-

tance in the bottom to eliminate any possibility of escape of sand.

If the bottom is particularly hard so that the lower edge is capable of penetrating only a short distance, I have found that the seal formed by the bottom material that extends upwardly within the skirt and the sand that may filter past the sand checks to fill the space beneath the segments, is capable of preventing leakage of sand from the shield, regardless of changing bottom conditions.

Where the bottom is sloping, the action explained above will also prevail and this is illustrated by the showing in Figs. 15 and 16 in which case the bottom material 68 has been washed away causing failure of lateral support for material 68 which under the pressure of the shield is forced laterally to the position shown in Fig. 16, thus permitting the bottom edge of the shield to remain embedded in the bottom.

The principle involved in the action just described is illustrated by the common experience had when one is standing in the surf on a sloping sand beach. The feet settle a certain distance in the sand until a position of equilibrium is reached. If the sand about the ankles is then washed away the feet will again settle a distance approximately the same as that obtained in the first position of equilibrium.

During the winter, the ice present in northern harbors tends to damage the upper sections which, as stated are of sheet material. If this situation develops I have devised a means and method of making repairs in a simple manner. The damaged portions are removed from the shield by merely drawing them upwardly from the section below, unbolting the joint and removing the shield from the pile. Because of the fact that, when initially installed, the telescoping sections fit quite snugly, it has been found difficult in inserting a new section to secure a satisfactory fit if using a section similar to the original. Instead I have found it more convenient to use a unit similar to that shown by section 70 in Fig. 19. This section has a funnel-like bottom, the smallest portion of which is substantially smaller than the upper end of the section into which it is to be inserted, but then broadens out sufficiently to limit the distance it may penetrate the section below. In the use of this section 70, I merely position it about the pile clamping the longitudinal joint together as in Fig. 2, and then lowering it down on the top remaining section of the original shield. Then, by pouring into section 70 additional sand, the shield is in condition to carry on until it may be again damaged by subsequent winters.

Fig. 20 illustrates a modified means for supporting one section on another. Instead of using the external hooks shown in Fig. 4, I have used internal hooks 72 which have, extending diagonally upward therefrom, the spacers 74. The hooks 72 are secured to section 6 by spot welding or in any other convenient manner and these hooks are spaced at such distances about the inner circumference of the section that they will be adequate to prevent the pile positioned within from touching the shield at any point. The spacers 74 operate in the same manner and have the same functions as spacers 20 heretofore described. This method of supporting the section provides adequate flexibility at the joint as was the case when using the hooks of the types shown in Fig. 4. Fig. 21 is a section on the line 21-21 of Fig. 20 showing the manner in which

the spacers prevent the pile from touching the wall of the shield.

By having a skirt of proper length, displacement upwardly of the sand checks by the bottom when the shield is initially lowered into place, is prevented. This is essential, for, if the segments were swung upwardly and disengaged from the pile, lateral shifting of the shield will take place. Obviously it takes but little movement sideways before the distance between the pile and shield at one point will exceed the length of a segment, and should this happen, the sand when poured in would force that segment unsupported by the pile, downwardly below the horizontal, thus creating a large void through which the sand could readily escape.

From the foregoing description of preferred forms of my invention it will be seen that I have provided an effective means for preventing destruction of submerged piling my amphipod Crustacea or other marine animals. In addition my structure is easy to make and install and the cost is far below that of installing a new pile. I have also provided a device which constantly maintains the sand sealed within the tube regardless of changing bottom conditions. I wish it to be distinctly understood, however, that I do not intend my invention to be limited to the precise forms shown but only by the appended claims.

I claim:

1. A pile shield comprising a plurality of flexibly connected tubular sections, a sectional bottom for said shield comprising a plurality of overlapping segments flexibly connected to said shield, auxiliary means for urging said segments downwardly whereby a pile positioned within said segments will be centrally located with respect to said shield and a skirt extending below said segments a substantial distance whereby penetration of the bottom by said skirt when said shield is unloaded will not exceed the distance from the lower edge of said skirt to said segments.

2. A pile shield comprising a tubular member adapted to be positioned about a pile, means for retaining loose material within said shield comprising a sectional bottom, said bottom formed from a plurality of inwardly extending overlapping segments flexibly connected to said shield, auxiliary means for urging said segments downwardly, and a skirt of substantial length extending below said bottom.

3. In a pile shield, a segmental bottom closure means comprising a plurality of segmental sections hingedly connected to said shield, said sections alternately overlying and underlying each other, the underlying sections having their radial edges rounded downwardly.

4. A tubular section for use with a pile shield comprising a tube formed of sheet material, means at one end of said section for maintaining said section in telescopic relation with the end of an adjacent section, and spacer means extending internally of said section to prevent a pile about which said section may be positioned from touching the inner wall of said section, the distance each said spacer means extends inwardly from said section wall being such that twice said distance plus the diameter of said pile is less than the internal diameter of said section.

5. A pile protector comprising a tube, means for maintaining the lower edge of said tube continuously embedded in the bottom in which said pile is positioned regardless of changes in the

adjacent bottom formation, said means comprising a bottom closure member of variable internal diameter attached to said tube and closing the space between said tube and said pile and positioned a substantial distance above the lower end of said tube, and means for urging said tube continuously downward comprising a quantity of finely divided loose material positioned between said tube and pile, the weight of which is substantially carried by said bottom.

6. A pile shield comprising a tubular member, a variable area closure member connected to said tubular member, said tubular member having a skirt extending a substantial distance below said closure member, and a plurality of internally extending spacers attached to said tubular member, said spacers being of insufficient length to center said pile with respect to said tubular member, but of such length and frequency to prevent said pile from touching said tubular member between said closure member and a predetermined point above.

7. A pile shield comprising a plurality of tubular sections mounted one on the other to form an articulated tube, each section being divisible throughout its length, the top of one section cooperating with the bottom of the section immediately above to produce a tight but flexible joint, a plurality of internally extending, circumferentially distributed spacers attached to at least one of said cooperating sections and providing means for maintaining said cooperating sections in mounted relation, said spacers being of such number and length as to prevent a pile about which said shield may be positioned from touching said shield at any point between the uppermost and lowermost spacers.

8. A pile shield comprising a plurality of substantially sand-tight tubular sections adapted to be positioned about a pile, means for closing the space between said shield and pile near the bottom of said shield, means for holding the lower end of said shield substantially concentric with said pile, a skirt attached to the lower end of said shield, said sections and skirt being substantially unobstructed longitudinally on their outer surfaces whereby the shield may settle into the bottom material under its own weight to a point of equilibrium, said closure means being positioned a sufficient distance above the lower edge of said skirt so as to be unaffected by said bottom material when said shield has reached said position of equilibrium.

9. The combination of a pile embedded in bottom material and a shield positioned thereabout and spaced from said pile by finely divided inert shiftable material, the lower end of said shield being embedded in said bottom material, closure means attached to said shield and separating said bottom material that is within said shield and said finely divided material, the combined weight of said shield and finely divided inert material being sufficient to move said shield and said material downwardly along said pile when a certain amount of bottom material surrounding said shield but above the lower end of said shield has been removed.

10. A pile protector comprising a tube, means for maintaining the lower edge of said tube continuously embedded in the bottom in which said pile is positioned regardless of changes in the adjacent bottom formation, said means comprising a bottom closure member of variable internal diameter and means for constantly urging said member to assume a position of maximum area

whereby it will fit closely and movably the pile about which said protector may be positioned, said bottom closure member positioned a sufficient distance above the lower edge of said tube so as to be unaffected in an upward direction by bottom material within said tube when said protector has settled to a point of equilibrium under the influence of its own weight, and means for moving said protector a further distance down said pile to a point of equilibrium at which the lower edge of said tube will always be embedded in the bottom material, said means for moving said protector comprising a quantity of finely divided loose material positioned between said tube and pile the weight of which is substantially carried by said bottom member.

11. A pile protector comprising a tube having its outer surface substantially unobstructed and its lower end adapted to penetrate the bottom in which said pile is embedded, closure means connected to said tube for tightly but slidably closing the space between said tube and pile, said closure means being positioned a substantial distance above the lower end of said tube whereby bottom material may form a seal within the lower end of said tube when said lower end is embedded in the bottom, means for moving said tube and sealing material downwardly along said pile upon the lowering of the bottom material surrounding said tube, said means comprising a quantity of finely divided loose material positioned within said tube and exerting its weight through said closure means, the effective downward force exerted by said tube and contained loose material always exceeding the frictional force existing between said closure means, loose material, and pile.

12. Means for retaining loose material about the submerged portion of a pile comprising a tubular member positioned about said pile and having its lower end arranged at an angle to approximate the slope of the bottom, said tubular member having a bottom closure member of variable internal diameter attached thereto, the inner circumference of said closure member closely engaging said pile, said bottom closure member being positioned a sufficient distance above the lower end of said tubular member to preclude engagement with the bottom after the unloaded tubular member has settled into the bottom to a position of equilibrium under the influence of its own weight.

13. A shield comprising a plurality of flexibly connected sections adapted to be positioned about a pile and to extend downwardly into the bottom a suitable distance, the lower section of said shield comprised of a plurality of divisible parts, each part having associated therewith movable members adapted to close the annular area between said pile and lower section, said members being positioned a substantial distance above the lower end of said bottom section, each upper section comprising a divisible tubular member, each upper section supported on the section below by a plurality of supports spaced about the lower circumference of each section, a plurality of internally extending spacers associated with each upper section, the distance between said spacers being such as to prevent said pile from engaging the walls of said sections at any point, said spacers extending inwardly a distance insufficient to center said pile with respect to said sections.

14. A protective device for a partially submerged pile comprising a tube about said pile

and spaced therefrom, the lower end of said tube being embedded a substantial distance in the bottom so that the bottom material forms a seal at the lower end of said tube, a bottom closure member of variable internal circumference associated with said tube, said closure member positioned a sufficient distance above the lower edge of said tube so as to be unaffected by bottom material within said tube when said device has settled to a point of equilibrium under the influence of its own weight, loose material substantially filling the space between said tube and pile, said tube through said bottom member assisting in carrying the weight of said loose material, the combined weight of said tube and said loose material being sufficient to maintain the lower end of said tube embedded in the bottom and to move said tube downwardly along said pile as surrounding bottom material is removed.

15. A method of protecting a pile comprising the steps of placing a tube about said pile, centering said pile with respect to said tube at its

lower end by means closing the annular area between said pile and tube, embedding the lower end of said tube in the bottom to a depth less than the distance from the bottom edge to said closure means, and finally filling the space between said pile and tube with finely divided shiftable inert material, thereby causing said tube and inert material to move downwardly about said pile a further distance to a point of equilibrium.

16. In a pile shield of tubular form a bottom closure means comprising a plurality of overlapping segmental sections, each section movably connected to the wall of said tube whereby each segmental section may be moved through a substantial arc, each of said segmental sections overlapping adjacent segmental sections, means for preventing movement of said segmental sections below a position substantially transverse of said tube, and auxiliary means urging said sections toward said transverse position.
